AUTOMOBILE LIFT

Elmer B. Thompson, Des Moines, Iowa, assignor
to Globe Hoist Company, Des Moines, Iowa, a
corporation of Iowa

Application July 30, 1938, Serial No. 222,227

15 Claims. (Cl. 254—89)

Substantially all of the automobile lifts now in use are of the so-called hydraulic type and employ an upright piston and cylinder which, when installed, projects to a considerable distance below the roadway or floor, and the cylinder is usually installed in solid concrete. If installed in a floor over a basement or room, the cylinder projects into the basement or room below and is, therefore, objectionable. If installed in rocky soil the installation is very expensive, and removal to a new location is also expensive.

The object of my invention is to provide a portable lift of such simple and inexpensive construction that it may be marketed competitively with hydraulic lifts, and at the same time may be quickly and easily installed by unskilled workmen upon any roadway or floor without occupying space below the floor.

A further object is to provide a lift of this class which, when the lift platform is in an elevated position, and if upon the breakage or failure of any part of the lift, the platform should start a rapid downward movement, the platform would be automatically locked and held after such rapid movement of only a few inches, so that no damage could result.

A further object is to provide a lift of this class in which in the event that any part of the platform during its normal downward movement should engage any obstruction the motor will be automatically shut off and further downward movement prevented.

A further object is to provide means whereby in the event that any one of the corner posts should be substantially out of vertical alignment, to such an extent as to cause undue friction or wear on the working parts, the mechanism for raising and lowering the platform will be automatically locked and the motor shut off, thereby preventing further operation and avoiding undue friction, wear or breakage until the uprights are returned to and fixed in substantially upright positions.

A further object is to provide an improved and simplified manually operated safety lock for holding the platform in its elevated position.

A further object is to provide simple and inexpensive means for automatically stopping the upward movement of the platform when it has reached its normally elevated position and in the event that the motor continues to operate thereafter.

In the accompanying drawings Figure 1 shows a perspective view of my improved automobile lift, parts of the beams of the platform being broken away to show structural details;

Figure 2 shows an enlarged detail view, partly in vertical section, illustrating the gear mechanism between the motor shaft and the drive shaft in the adjacent transverse platform beam;

Figure 3 shows a transverse sectional view of same;

Figure 4 shows an inner face view, partly in section, of one of the corner upright posts and illustrating the gear mechanism and the automatic safety locking mechanism and the manually operated locking mechanism, taken on the line 4—4 of Figure 5;

Figure 5 shows a vertical sectional view of same taken on the line 5—5 of Figure 4;

Figure 6 shows a view somewhat similar to Figure 4 and illustrating the corner post at the corner where the electric motor is installed, and illustrating the switch mechanism for automatically shutting off the motor, and also illustrating in detail the rack bar and pinion for operating the switch;

Figure 7 shows an enlarged detail vertical sectional view of the safety lock escapement device taken on the line 7—7 of Figure 8;

Figure 8 shows a horizontal sectional view of one of the corner posts and illustrating the safety locking mechanism therein; and

Figure 9 shows a detail view illustrating the locking bar and the levers which support the clutch jaws and a portion of the platform, and illustrating the manner in which the said levers are caused to grip the locking bar when the adjacent portion of the platform is tilted out of a horizontal position.

My improved lift device comprises four upright corner posts, each of which is preferably independently fixed to the floor or roadway on which the lift is mounted. Each comprises a base plate 10 and an upright corner post 11. This corner post is preferably made of plate metal and is rectangular in outline, and on its inner surface it is formed with a vertical slot 12, the edges of the metal adjacent the slot being bent inwardly at 13 toward the center of the post and then parallel with the adjacent side of the post, as shown at 14 in Figure 8. One of the corner posts adjacent the corner to which the electric motor is applied is formed with an additional slot 15 on the side opposite from the slot 12, as shown in Figure 3. At the top of each of the corner posts is a plate 16 firmly fixed in position.

The platform comprises two transverse beams 17 and two longitudinal beams 18, all rigidly fixed together to form a substantially rigid platform. The transverse beams 17, as shown in Figure 4, are hollow. Firmly fixed to each end of each of the transverse beams 17 is an upright bracket 19. Fixed to the outer surface of the bracket 19, as shown in Figure 5, is a block 20, and fixed to the outer surface of the block 20 is a bearing plate 21. Mounted in the block 20 and the bearing plate 21 is a stationary shaft 22 extended outwardly and fixed in position by the set screw 23. Rotatably mounted upon the shaft 22 is a

gear wheel 24, and fixed to this gear wheel is a toothed pinion 25. Extended longitudinally through the beam 17 is a shaft 26 having fixed thereto a pinion 27 in mesh with the gear 24.

5 An electric motor 28 is mounted at one corner of the lift, and its shaft 29 extends downwardly through a casing 30 in which it is rotatably mounted, and a worm gear 31 is mounted at its lower end portion. This worm gear is in mesh 10 with the large worm gear 32 rotatably mounted on the shaft 33 within the casing 30, as shown in Figures 2 and 3.

15 On this shaft 33 is a small pinion 34 mounted in the casing 30, and the pinion 34 is in mesh with the large gear 35 fixed to the adjacent shaft 36. This shaft 36 is, as shown in Figure 1, extended through the adjacent transverse beam 17 to the corner post 11 opposite the one to which the motor is attached, and a beveled gear 37 20 is fixed to the shaft 36. Within one of the longitudinal beams 18 is a shaft 38 having at one end a beveled gear 39 in mesh with the beveled gear 37. This shaft 38 extends to the opposite one of the transverse platform beams 17 and is 25 provided with a beveled pinion 40 in mesh with a beveled pinion 40 on the shaft 26 within the other beam 17.

By this means it will be seen that on rotation 30 of the motor both of the shafts 36 and 26 will be correspondingly rotated at a speed greatly reduced from that of the motor shaft, and they will all be rotated in unison.

35 In Figure 6 I have shown at the top of the upright corner post adjacent the motor 28 an electric switch 41 of ordinary construction. This switch is arranged in the circuit of the motor 28, and when the switch is elevated the circuit is open, the switch being normally held in its lower position to close the circuit by means of the spring 42. I have not herein illustrated the wiring connections between the switch and the motor. These, however, are of the ordinary construction.

40 For guiding the platform within the corner posts I have provided grooved guide rollers 43 mounted on the bolts 44 which are fixed to the bearing plates 21, as shown in Figure 5. These grooved rollers enter and operate in the slots 12 in the corner posts, as shown in Figures 5 and 8.

45 In each of the corner posts there is a rack bar, indicated by the numeral 45. This rack bar is formed with a series of openings 46 to receive the teeth 47 of the pinions 25, as shown in Figure 6. At the top portion of the rack bar there is arranged in line with the openings 46 a slot 48, shown in Figure 5. The rack bar extends upwardly through the top plate 16, as shown in Figure 6, and at its top is a collar 49 held in place by a set screw 50 and resting on the top plate 16.

50 The lower end of the rack bar is free so that the rack bar is suspended on the top plate 16 and is free to move upwardly but not downwardly from its normal position. The upper end of the rack bar 45 is positioned directly below the switch 41.

55 so that when the rack bar is slightly elevated above its normal position it will operate the switch to open the circuit.

60 With the construction heretofore described, and assuming that the motor is being operated to raise the platform it will be seen that the pinions 25 at all four corners of the platform will engage the rack bars 45, and since all the pinions 25 are operated at uniform speed, the platform will be elevated equally at all corners, and when 65 the pinions are elevated to their normal upward

limit, the teeth 47 of the pinions 25 will enter the slots 48 and thereby prevent further upward movement of the platform even though the motor is operating, and when the downward movement is commenced the teeth 47 will enter the 5 openings 46 in the rack bar and move the platform downwardly in a horizontal position.

6 In the event that there should be a failure of any part of the mechanism, such, for instance, as a breakage of the shafts, which control the 10 pinions 25, or breakage of one or more of the rack bars 45, it is essential that further downward movement of the platform be immediately stopped and the platform locked in the elevated position in which said failure occurred. For this 15 purpose I have provided the following mechanism:

7 Mounted in each of the corner posts is a locking bar 51 extended through the plate 16 and provided with a collar 52 held in place by a set 20 screw 53, the lower end of the locking bar being free. This locking bar is, as illustrated in Figure 8, rectangular in outline with two relatively wide side edges and two relatively narrow edges, and it is smooth. Adjacent the locking bar 51 is 25 an escapement bar 54. This escapement bar extends upwardly through the plate 16 and is provided with a collar 55 held in place by a set screw 56. The lower end of the escapement bar is free. This escapement bar, as shown in Figure 8, is substantially rectangular in outline and throughout its length it is formed with a series of uniform symmetrical alternately arranged curves 57, as shown in Figure 7.

8 Attached to and carried by the bracket 19 is a 35 plate 58, and pivoted to this plate 58 are two levers 59. These levers are extended horizontally on opposite sides of the locking bar 51, as shown in Figures 4 and 5, and their inner surfaces are smooth and in loose frictional engagement with the flat sides of the locking bar 51. Pivotally mounted between the outer ends of the levers 59 is a clutch jaw 60, shown in Figure 4. This clutch jaw is smooth on its surface adjacent the locking bar and in normal position is in loose frictional 45 engagement with the said locking bar; and pivotally mounted between the levers 59 is a second clutch jaw 61, smooth on its edge adjacent the locking bar and normally in loose frictional engagement therewith. Fixed to the clutch jaw 61 50 is a bracket 62, shown in Figure 6, and on this bracket is a rod 63 to which is pivoted a rectangular escapement frame 64 which extends upwardly and has pivotally mounted on its upper end an escapement shaft 65. This shaft has at 55 one end a loop 66, as shown in Figure 8, and this loop encircles the escapement bar 54 and loosely fits it. On the other end of the escapement shaft 65 is a weight 67 extended transversely of the shaft. The parts of this escapement device are 60 so proportioned relative to each other and to the curved portions in the escapement bar that during the normal up or down movement of the platform at the speed at which it is normally driven by the motor and reduced gearing mechanism, 65 the curved portions of the escapement bar will engage the loop of the escapement shaft and cause it to rock and to thereby oscillate the weight 67, and this is done with a very slight amount of friction or loss of power. When, however, the platform commences to descend at a high rate of speed, such, for instance, as when 70 such failure on the part of the elevating mechanism occurs as would cause the platform to drop by gravity, then the inertia of the escapement 75

weight would prevent it from oscillating in the manner in which it is normally oscillated by the escapement bar, and, hence, the escapement loop would be locked upon the escapement bar and would tend to remain in its elevated position. At this time the plate 58 connected to the platform, and the levers 59 connected to the plate 58 would remain stationary, and since the escapement frame is connected to the clutch jaw 61, this clutch jaw would be held stationary, and when this has happened, the outer ends of the levers 59 would be moved downwardly and, hence, the clutch jaw 60 would be moved toward the adjacent edge of the locking bar 51 and they would jointly be moved toward the clutch jaw 61 into firmly gripping and locking contact therewith, and further descent of the elevator platform would be prevented.

The said levers 59 perform a somewhat similar locking function as follows:

It sometimes happens that, as illustrated in Figure 1, an obstruction, such, for instance, as a box, 68, is placed on the floor in the path of one of the platform beams, and during the normal descent of the platform and when the platform engages this obstruction it will, of course, prevent further downward movement of that part of the platform which engages the obstruction. The opposite corner of the platform, however, may continue to be moved downwardly, and this causes a tilting of the beam 17, as shown in Figure 1. In Figure 9 I have illustrated the plate 58 attached to one corner of the platform in a slightly tilted position relative to the upright lock bar, and since the levers 59 are carried by the plate and lie flat against the adjacent surfaces of the plate 58, the tilting of this plate 58 from the vertical position will tend to twist the levers 59 relative to the upright locking bar and thereby form a gripping engagement with the locking bar 51, then as the platform moves a slight distance the levers thus held will bring the clutch jaws into locking engagement with the locking bar, thereby preventing further downward movement and avoiding injury to the apparatus. When the locking bar is thus gripped and held by the levers 59, and the motor continues to operate, the adjacent rack bar 45 is moved upwardly. If it should happen that such upward movement of the rack bar is applied to the particular rack bar on the corner post adjacent the motor, then, obviously, the switch mechanism 41 will at once be operated to open the circuit. I have not applied a switch device 41 to each of the corner posts on account of the expense involved in so doing, but I have found in practice that this is unnecessary because when the conditions occur as before described and as illustrated in Figure 1, and further downward movement of the platform is prevented, then the rack bars will, one after the other, be elevated to their limit and eventually the rack bar beneath the switch bar 41 will also be elevated and the circuit opened, and I have found in practice that this can be done repeatedly without any injury to the mechanism, hence, it is unnecessary to have more than one switch device.

A number of my improved lifts as herein illustrated are now in constant use and are operating satisfactorily and efficiently. I have repeatedly placed a four ton truck on my lift, and when the motor is running in one direction, the lift and its weight are slowly elevated, and when the motor is reversed, they are slowly lowered.

During this time the escapement device oscillates in unison with the escapement bar and causes only a minimum of friction and wear. I have repeatedly demonstrated that under the above conditions and when some part of the mechanism is removed to permit the platform and its weight to drop, at the instant when the rapidly oscillated downward movement commences, the escapement weight, due to its inertia, will not operate in time with the movement ordinarily imparted to it by the escapement shaft, and, hence, the escapement loop will bind upon the escapement bar and lock the escapement device to the escapement bar, and the clutch jaws will engage the locking bar in such manner as to stop further downward movement of the platform within a very few inches, and no injury to the apparatus occurs under such conditions. I have also demonstrated that even though the locking bar and the clutch jaws were covered with oil, the binding force applied to these lock bars is sufficient to cause the gripping jaws to lock in their position and prevent such further downward movement.

In practice it sometimes occurs, after a mechanic has been working on the under side of an automobile upon the platform, that articles are left beneath the platform, such, for instance, as the mechanic's tool chest, and I have repeatedly demonstrated in actual practice that when this occurs and the motor is still running in the direction for lowering the lift, and when the downward movement of any one corner of the lift is thereby stopped, the rack bar in the upright post adjacent the motor will be elevated to throw the switch when the corner of the platform under which the obstruction has been placed is held only a few inches above the other corners of the platform, and that this tilting movement of the platform relative to the corner posts does not in any way injure the apparatus.

I have provided a manually operated platform locking device as follows: 70 indicates a locking bar loosely mounted in slots in the upright 11, said slots having one extension 71 extended downwardly and into the path of the platform, and another extension 72 extended downwardly and out of the path of the platform; a spring 73 holds the locking bar downwardly. On the platform is a hook 74 with an inclined surface 75 above it to engage the bar 70 and move it upwardly and laterally in the slot 71. When the bar 70 is in the slot extension 71 and the hook 74 engages it from above, the platform is locked in its elevated position.

In the event that an operator is required to work beneath the platform when in its elevated position, then the operator may grasp the manually operated lock bar and move it to its inwardly extended position in the path of the safety hook, and then when the platform arrives at a lower position it is automatically locked and there held, and when it is desired to lower the platform, it is first raised by the motor to release the locking hook from the locking bar, and then the locking bar is manually moved to position out of the path of the locking hook.

My improved lift is portable and can be installed on a floor by unskilled workmen very quickly and easily and with a minimum of expense and, as frequently happens, after it has been once installed it is desirable to move it to a new location. One of the reasons why it is easy to erect and install my improved lift is that if it should happen that during the installation the

uprights were not in a substantially vertical position and the motor was started, then the levers 59 would exert their gripping action upon the locking rod and prevent the operation of the lift without any injury thereto, but, of course, when this occurs, the operator installing the elevator would be required to place all of the uprights in substantially vertical positions before it can be made to operate, but after it has been installed 10 in such a manner that it will operate, I have found that the uprights will stay in substantially upright position without further attention by the operator and, obviously, this simple and inexpensive installation as compared with the installation 15 of a hydraulic lift is an important factor.

Any of the ordinary escapement devices and operating bars may be used in my lift for actuating the clutch jaws.

I claim as my invention:

20 1. In a lift apparatus, the combination of an upright support, a platform mounted upon the support for vertical movement, power-operated mechanism for moving the platform up and down at relatively low speed, and means for automatically locking the platform against downward movement at relatively higher speeds, said means comprising an upright escapement bar, an escapement device carried by the platform and capable of being operated as an escapement by the escapement bar during the normal speed of travel of the platform and permitting the escapement device to move vertically relative to the escapement bar and also capable of becoming inoperative as an escapement when the speed of travel of the platform becomes excessive and under such conditions of becoming fixed to the escapement bar, an upright locking bar, a clutch jaw operatively associated with the locking bar, means carried by said platform and connected to said clutch jaw for moving the clutch jaw toward and from the locking bar, and means for operatively connecting the escapement device to said clutch jaw for moving the clutch jaw into locking engagement with the locking bar when the said platform moves downwardly and the escapement device is held by the escapement bar against downward movement.

25 2. In a lift apparatus, the combination of an upright support, a platform mounted upon the support for vertical movement, power-operated mechanism for moving the platform up and down at relatively low speed, and means for automatically locking the platform against downward movement at relatively higher speeds, said means comprising an upright escapement bar, an escapement device carried by the platform and capable of being operated as an escapement by the escapement bar during the normal speed of travel of the platform and permitting the escapement device to move vertically relative to the escapement bar and also capable of becoming inoperative as an escapement when the speed of travel of the platform becomes excessive and under such conditions of becoming fixed to the escapement bar, an upright locking bar, a clutch jaw operatively associated with the locking bar, means carried by said platform and connected to said clutch jaw for moving the clutch jaw toward and from the locking bar, and means for operatively connecting the escapement device to said clutch jaw for moving the clutch jaw into locking engagement with the locking bar when the said platform moves downwardly and the escapement device is held by the escapement bar against 30 downward movement, said escapement bar being

suspended from its upper end and free at its lower end.

3. In a lift apparatus, the combination of an upright support, a platform mounted upon the support for vertical movement, power-operated mechanism for moving the platform up and down at relatively low speed, and means for automatically locking the platform against downward movement at relatively higher speeds, said means comprising an upright escapement bar, an escapement device carried by the platform and capable of being operated as an escapement by the escapement bar during the normal speed of travel of the platform and permitting the escapement device to move vertically relative to the escapement bar and also capable of becoming inoperative as an escapement when the speed of travel of the platform becomes excessive and under such conditions of becoming fixed to the escapement bar, an upright locking bar, a clutch 20 jaw operatively associated with the locking bar, means carried by said platform and connected to said clutch jaw for moving the clutch jaw toward and from the locking bar, and means for operatively connecting the escapement device to said clutch jaw for moving the clutch jaw into locking engagement with the locking bar when the said platform moves downwardly and the escapement device is held by the escapement bar against downward movement, said locking bar 30 being suspended at its upper end and free at its lower end.

4. In a lift apparatus, the combination of an upright support, a platform mounted upon the support for vertical movement, power-operated mechanism for moving the platform up and down at relatively low speed, and means for automatically locking the platform against downward movement at relatively higher speeds, said means comprising an upright escapement bar, an escapement device carried by the platform and capable of being operated as an escapement by the escapement bar during the normal speed of travel of the platform and permitting the escapement device to move vertically relative to the escapement bar and also capable of becoming inoperative as an escapement when the speed of travel of the platform becomes excessive and under such conditions of becoming fixed to the escapement bar, an upright locking bar, two parallel levers pivoted at one end to the platform and arranged on opposite sides of the locking bar, a clutch jaw pivoted between the outer ends of said lever and adjacent one side of the locking bar, a second clutch jaw pivoted between said levers adjacent the opposite edges of the locking bar, said escapement device including a frame in which it is supported, and said frame being pivotally connected to the last mentioned clutch jaw.

5. In a lift apparatus, the combination of an upright support, a platform mounted upon the support for vertical movement, power-operated mechanism for moving the platform up and down at relatively low speed, and means for automatically locking the platform against downward movement at relatively higher speeds, said means comprising an upright escapement bar, an escapement device carried by the platform and capable of being operated as an escapement by the escapement bar during the normal speed of travel of the platform and permitting the escapement device to move vertically relative to the escapement bar and also capable of becoming inoperative as an escapement when the speed of travel of the platform becomes excessive and 70

under such conditions of becoming fixed to the escapement bar, an upright locking bar, two parallel levers pivoted at one end to the platform and arranged on opposite sides of the locking bar, a clutch jaw pivoted between the outer ends of said lever and adjacent one side of the locking bar, a second clutch jaw pivoted between said levers adjacent the opposite edges of the locking bar, said escapement device including a frame 5 in which it is supported, and said frame being pivotally connected to the last mentioned clutch jaw, the adjacent faces of said levers being positioned so close to the sides of said locking bar that when the platform to which the levers are 10 pivoted is tilted a substantial distance relative to the locking bar in one direction, said levers will exert a clutching and locking action upon the locking bar.

6. In a lift of the class described, the combination 15 of an upright support, a platform, an upright rack carried by the upright support and capable of independent vertical movement relative thereto, a pinion carried by the platform and in mesh with the rack, a motor for rotating said pinion, said parts being so arranged and positioned that when downward movement of the platform is stopped while the motor continues to operate, the pinion will move the rack upwardly, and a switch device for starting and stopping the 20 motor operatively connected to the rack for moving the switch device to inoperative position when the rack is moved upwardly.

7. In a lift device, the combination of an upright, a platform, a rack bar suspended at its upper end upon the upright support and capable 25 of moving upwardly relative to the support, an electric motor carried by the platform, a pinion operatively connected to the motor and in mesh with the rack, and an electric switch in the electric motor circuit positioned to be moved to open 30 position when said rack is moved upwardly.

8. In a lift, the combination of four upright corner posts, a rack bar suspended at its upper end within each corner post, one of said rack bars 35 being capable of upward movement relative to its post, a platform, an electric motor carried by the platform, a pinion in mesh with each of said rack bars, gearing mechanism connecting the motor with each of said pinions, and an electric switch 40 in the motor circuit positioned to be operated upon upward movement of said movable rack bar for opening the circuit and whereby when downward movement of the platform is stopped with the motor still running, the circuit will be broken 45 and the motor stopped.

9. In a lift apparatus, the combination of four corner uprights, a platform between the uprights, an upright rack bar in each corner upright, a pinion carried by the platform at each corner 50 thereof and in mesh with the adjacent rack bar, means for jointly rotating said pinions, a hook carried by the platform, a locking bar manually 55 movable from position out of the path of the said hook to position in the path thereof, and a spring applied to said locking bar for holding it in position to enter said hook when the latter approaches said bar from above.

10. In a lift apparatus, the combination of four corner uprights, a platform between the uprights, an upright rack bar in each corner upright, a pinion carried by the platform at each corner thereof and in mesh with the adjacent rack bar, means for jointly rotating said pinions, a plate carried by the platform at one corner and formed

with a notch and with a downwardly inclined surface above the notch, a locking bar near the top of the upright adjacent said plate, the upright being formed with slots in which said locking bar is loosely mounted, said slots being formed 5 with one extension inclined downwardly and toward the path of said hook, and also with another extension inclined downwardly away from the path of said hook, and a spring fixed to the locking bar and extended downwardly and fixed to the upright.

11. In a lift apparatus, the combination of an upright support, a platform movable vertically relative to the upright, an escapement device 10 carried by the platform, means for operating the escapement device during normal vertical movements of the platform, an upright locking bar, a clutch jaw carried by the platform to cooperate with the locking bar, and means for moving the clutch jaw into locking engagement with the locking bar, said means being actuated by said escapement device when the platform moves downwardly at a speed greater than normal.

12. In a lift apparatus, the combination of a support, a vertically movable platform on the support, an escapement device, means for operating it as an escapement during the vertical movements of the platform at normal speeds, a gripping device for holding the platform against vertical movement, and means actuated by said escapement when the platform is moved at a speed greater than normal for moving the gripping device to position for stopping further downward movement of the platform.

13. In a lift apparatus, the combination of a support, a vertically movable platform on the support, an escapement device, a weight forming part of said escapement device and controlling same by its inertia, means for operating it as an escapement during the vertical movements of the platform at normal speeds, a gripping device for holding the platform against vertical movement, and means actuated by said escapement when the platform is moved at a speed greater than normal for moving the gripping device to 40 position for stopping further downward movement of the platform.

14. In a lift apparatus, the combination of an upright support, a platform vertically movable relative to the support, an upright rack bar suspended from the upper portion of the upright and free at its lower end, a pinion carried by the platform and in mesh with the rack bar, and means for operating the pinion, said parts being so shaped and arranged that when the pinion is 50 rotating in a direction for moving the platform downwardly, and downward movement of the platform is prevented, the pinion will elevate the rack bar.

15. In a lift apparatus, the combination of an upright support, a platform vertically movable relative to the support, an upright locking bar, two levers on opposite sides of the locking bar and carried by the platform, a gripping jaw carried by said levers and capable of being moved by 60 said levers into gripping engagement with the locking bar, said levers being so positioned that when the platform is tilted relative to the upright they will frictionally engage the locking bar so that further movement of the platform will cause 65 the levers to bring the clutch jaw into locking engagement with the locking bar.
